Veamor All-in-One Picture Hanging Kit, Date Visited: Sep. 19, 2022, Amazon, Date Available: Mar. 31, 2021, <https://www.amazon.co.uk/VERMOR-Multifunction-Picture-Hanging-Tool/dp/B091GQ8YNH> (Year: 2021).*Primary Examiner — Karen S Acker*Assistant Examiner* — Elizabeth S Ko(74) *Attorney, Agent, or Firm* — Jeenam Park(57) **CLAIM**

The ornamental design for a picture hanging tool, substantially as shown and described.

DESCRIPTION

FIG. 1 is a top, front and left side perspective view of a picture hanging tool, showing my new design;

FIG. 2 is a bottom, front and left side perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a rear elevational view thereof; and,

FIG. 8 is a front elevational view thereof.

The broken lines in the drawings illustrate the portions of the picture hanging tool, which form no part of the claimed design.
